EXPOSURE TIMER FOR X-RAY APPARATUS

Samuel A. Johnston, Walworth, Wis., assignor to
The George W. Borg Corporation, Chicago, Ill.,
a corporation of Delaware

Application April 10, 1950, Serial No. 155,105

13 Claims. (Cl. 250—27)

1

The present invention relates in general to exposure timers for X-ray apparatus, such as are used for controlling the duration of X-ray exposures, and the object of the invention is a new and improved timer of this character.

A feature of the invention is an electronic timer in which a time interval is measured by the discharge of a condenser through a resistance the value of which may be preadjusted in accordance with the desired duration of the time interval.

Other features relate to circuit arrangements designed to protect against over exposure or failure of various equipment items to operate in the intended manner.

The invention will be described more fully in the ensuing specification with reference to the accompanying drawing, which is a conventional circuit diagram showing an X-ray installation embodying the invention.

Referring to the drawing, the reference characters 1 and 2 indicate a single phase power line, supplying commercial alternating current at a voltage of about 115 volts. The reference character S1 indicates a switch for connecting the line through to the conductors 3 and 4 and 5 and 6 over which alternating current is supplied to the apparatus. S2 is the X-ray exposure switch.

The X-ray tube is indicated at 10 and may be of any suitable type. Anode current for the X-ray tube is supplied by the high tension transformer 12 the primary winding of which may be energized from the auto-transformer 13 which is bridged across the conductors 5 and 6. The connections between the primary winding of transformer 12 and the auto-transformer 13 are normally open and may be closed by energization of the relay 14.

The filament current for the X-ray tube is supplied by the transformer 11, under control of the milliampere selector switch, labeled "M. A. selector" in the drawing. The milliampere selector is a manually adjustable rotary switch having a contact arm 15, a plurality of contacts adapted to be engaged successively by rotation of the contact arm, and a plurality of resistors such as 19 which connect these contacts. The milliampere selector is bridged across the conductors 5 and 6 in series with the primary winding of the transformer 11 and is used in known manner to adjust the load on the X-ray tube prior to making an exposure. As shown in the drawing the load may be varied from 25 milliamperes to 250 milliamperes, but the arrangement shown is merely illustrative and may be changed when necessary or desirable.

The milliampere selector is preferably provided with additional contact arms 16, 17, and 18 and an associated set of contacts the purpose of which will be explained. The contact arms 16—18 are mechanically connected to contact arm 15, as

2

by mounting them on the same shaft, so that all said contact arms rotate together.

The electronic timer includes a timer selector switch, labeled "Time selector" in the drawing, which is a manually adjustable rotary switch having a contact arm 30 and a plurality of contacts associated therewith as shown. These contacts are connected by the resistors 32—35. The timer also includes the condenser 36 which may have a capacity of 4 microfarads. The condenser has a charging circuit including the resistor 48 and a discharging circuit which includes the resistor 31 and one or more of the resistors 32—35, depending on the adjustment of the time selector switch. These circuits will be explained more fully hereinafter.

The reference character 38 indicates a space discharge device which may be a type 1J6 triode. Heater current for the cathode of the tube is supplied by the transformer 39, the primary winding of which is bridged across conductors 5 and 6.

The reference character 45 indicates a rectifier the purpose of which is to provide direct current for the anode circuit of tube 38 and for the charging circuit of the condenser 36. The conductors 6 and 7 may be considered as the direct current output conductors and the rectifier is so connected that the conductor 7 is positive with respect to conductor 6. The condenser 47 is connected between the conductors 6 and 7 and functions to maintain a more or less ripple free positive potential on conductor 7. For this purpose it should have a fairly large capacity, on the order of 10 to 20 microfarads.

The resistors 42 and 44 and the potentiometer 43 are bridged across the conductors 6 and 7 and are provided to complete the cathode anode circuit of tube 38. For this purpose the slider of the potentiometer is connected to the mid point of the secondary winding of the transformer 39. The potentiometer 43 also makes it possible to adjust the cathode potential to the proper value.

Relay 40 is a direct current relay connected in the anode circuit of tube 38. Relay 41 may be any suitable type of relay adapted to operate on alternating current, as is the relay 14 previously mentioned.

The grid resistor 37 should be of very high resistance, preferably on the order of 20 megohms. Resistors 46 and 48 are small protective resistors which may have values of about 50 and 200 ohms, respectively.

The operation of the timer and associated parts will now be explained, it being assumed for this purpose that a picture is to be taken by means of X-rays in known manner.

When the switch S1 is closed, alternating current is supplied to the conductors 3 and 4 and 5 and 6, thereby energizing the auto-transformer 13. The high voltage transformer 12 is not energized for the time being, since relay 14 is deener-

gized. Alternating current is also supplied to the rectifier 45, and the condenser 47 becomes charged, whereby conductor 7 is maintained at a substantially constant positive potential with respect to conductor 6. The condenser 36 accordingly charges over a circuit which extends from conductor 6 by way of conductor 50, the said condenser, resistor 48, and back contact of relay 41 to conductor 7. The charging time is relatively very short, due to the low value of resistor 48. It will be noted that there is a leakage path to conductor 6 by way of contact arm 30 of the time selector switch and resistor 31 but the resistance of resistor 31 is so high relative to the resistance of resistor 48 that the condenser 36 becomes charged substantially to the potential of conductor 7.

Alternating current is also supplied to the transformer 39, which supplies current for heating the cathode of tube 38. Direct current also flows over a path which includes the resistor 44, the potentiometer 43, and the resistor 42, and the drop across the resistor 44 and the adjacent part of the potentiometer winding is effective to produce a potential at the cathode of tube 38 which is positive with respect to conductor 6. The proper value of this potential varies with the characteristics of the tube and may be adjusted by means of the potentiometer. It should be high enough so that the tube will cut off when the grid potential, although necessarily lower than the cathode potential, is nevertheless considerably higher than the potential on conductor 6. When a type 1J6 tube is used the cathode potential may be on the order of about 35 volts.

The condenser 36 being charged, a positive potential is applied to the grid of tube 38 over a circuit which includes the contact arm 30 of the time selector switch, the contact on which the contact arm is resting, one or more of the resistances 32-35, and the resistor 31. Some grid current can flow over the above circuit but the current is very small due to the extremely high resistance of the circuit as traced. This resistance also reduces the positive potential on the grid to a low value, but the grid potential is nevertheless higher than the cathode potential because of the drop across the space discharge path between the cathode and grid. Although the grid is therefore positive with respect to the cathode no current flows in the anode circuit of the tube because it is open at contacts of relay 41.

After the operator has closed the switch S1 with the results described, he will adjust the milliampere selector switch in accordance with the load required by the particular conditions under which the picture is to be made. It may be assumed in the present case that the milliampere selector is adjusted for a medium load of 100 milliamperes, as shown in the drawing.

The operator may then adjust the time selector switch in accordance with the desired exposure time, which may be assumed to be the minimum time interval of $\frac{1}{4}$ second. In this case also the switch is shown in the adjusted position assumed.

Having adjusted the milliampere selector switch and the timer selector switch, and other necessary preparations having been made, the operator may now close the switch S2 to make the exposure. The switch must be held closed until the exposure is completed.

When the switch S2 is closed, it completes an obvious circuit for the relay 41. Upon energizing, relay 41 disconnects the positive conductor 7 from the condenser 36 and connects it instead

to the relay 40. A positive potential is thus applied to the anode of tube 38 through relay 40, current starts to flow in the cathode anode circuit of the tube, and relay 40 is energized. Upon energizing, relay 40 completes a circuit for relay 14, which energizes and closes the connections between the auto-transformer 13 and the primary winding of the transformer 12. The transformer 12 is thus made operative to supply high voltage current to the anode circuit of the X-ray tube and the exposure begins.

When the positive conductor 7 is disconnected from the condenser 36 by relay 41, the condenser starts to discharge through the resistor 31. At the beginning of the discharge the condenser is charged substantially to the potential of conductor 7, whereby the grid of tube 38 is made slightly positive with respect to the cathode in the manner explained. As the condenser discharges through resistance 31, the grid potential does not change appreciably until the potential on the condenser becomes equal to the cathode potential. At this point the flow of grid current ceases and as the discharge of the condenser continues the grid potential follows the condenser potential and very quickly becomes sufficiently negative with respect to the cathode potential to greatly reduce the anode current and cause relay 40 to deenergize. Upon deenergizing, relay 40 breaks the circuit of relay 14 which deenergizes also to interrupt the supply of current to transformer 12 and terminate the exposure.

The operator may now release the switch S2, causing relay 41 to deenergize. This opens the anode circuit of tube 38 and re-establishes the charging circuit of condenser 36. The condenser accordingly charges again to prepare for another timing operation. It will be noted that the operator has to hold the switch S2 in operated position during the exposure. In the case described, where the exposure time is only $\frac{1}{4}$ second, the time during which the switch must be held operated is insignificant but it becomes appreciable on long exposures on the order of 5 seconds or more. Relay 41 could be provided with a locking circuit controlled by relay 40 if desired, so that only a momentary actuation of switch S2 would be required regardless of the duration of the exposure to be made, but the arrangement shown is preferred on account of its simplicity and because it enables the operator to instantly stop the exposure by merely releasing the switch in case anything should go wrong.

It will be understood that the resistance value of resistor 31 is so selected that the time interval measured by the discharge of condenser 36 through this resistor is $\frac{1}{4}$ second, corresponding to the setting of the time selector switch. The value of the resistance of course depends on the operating voltage and on the capacity of the condenser, but it may be stated that in the timer described a resistor 31 having a resistance of 47,000 ohms has been found to give the required time interval of $\frac{1}{4}$ second.

The time interval is substantially independent of ordinary fluctuations in the supply voltage. For example, an increase in voltage which would increase the charge in condenser 36 and tend to prolong the time interval is compensated by an increase in the cathode potential which decreases the extent to which the condenser has to discharge and tends to shorten the time interval.

The time interval can be increased from $\frac{1}{4}$ second to any desired time interval within a considerable range by inserting additional resistors

in the discharge circuit. This is the function of the time selector switch. The drawing shows a range up to 5 seconds but this could be increased to about 10 seconds if desired without increasing the capacity of the condenser 36.

It may be pointed out, moreover, that operation over this range is accomplished without requiring the condenser to discharge more than about two-thirds of the charge accumulated when it is fully charged. This means that the discharge curves for various resistance values are substantially linear with respect to time, that is, the condenser is never required to discharge far enough so that its discharge curve becomes essentially non-linear. The limitation on the extent of condenser discharge required is accomplished by maintaining the cathode potential at tube 38 at a relatively high value, as will readily be understood.

In view of the foregoing explanation it will be clear that the increase in resistance values required for increasing time intervals is substantially linear also. Thus the resistor 32 may have the same value as resistor 31, and when the time selector switch contact arm 30 is moved to its $\frac{1}{2}$ second contact, thereby doubling the resistance in the discharge circuit, the time interval will be doubled also. When the contact arm 30 is adjusted to its 1 second contact the selected time interval is doubled again and consequently the resistor 33 should be equal in resistance to the combined resistances of resistors 32 and 31. Similarly, resistor 34 should have a resistance equal to the combined resistances of resistors 33, 32, and 31. For time intervals longer than 2 seconds the resistance per second has to be increased somewhat, due to a slight departure of the discharge curves from linearity and to the increasing effect of the grid current which although extremely low is nevertheless effective over a long time interval to supplement the normal discharge path of the condenser to an appreciable extent. Thus whereas the resistance value for time intervals up to 2 seconds should be about 188,000 ohms per second, this value should be increased to about 200,000 ohms per second for time intervals in the range of 3 to 5 seconds, and to 220,000 ohms per second for time intervals in the range of 6 to 10 seconds. In the timer described these resistance values have been found to give time intervals which are accurate within plus or minus 5%.

In the explanation so far it has been assumed that the milliamperc selector remains adjusted for a load of 100 milliamperes while the time selector is adjusted for various exposure times in the range available. If the milliamperc selector is now adjusted for a load of 150 milliamperes the contact arm 18, which rotates with contact arm 15, will short circuit the resistance 35 at the time selector switch, thereby limiting the time interval which can be selected by this switch to 2 seconds. The time selector can of course be set on its 5 second contact but such adjustment is ineffective to introduce resistor 35 into the condenser discharge circuit because the resistor has been short circuited. Similarly, the setting of the milliamperc selector for a load of 200 milliamperes will limit the exposure time interval to 1 second by short circuiting resistors 34 and 35, while the setting of the milliamperc selector for a load of 250 milliamperes will limit the exposure time interval to $\frac{1}{2}$ second by short circuiting resistors 33, 34, and 35.

The operator is provided with information 75 including means for maintaining a potential on

which shows the duration of exposure which is permissible with each setting of the milliamperc selector and will be careful not to exceed the limit in any case, but if a mistake is made the circuit arrangement described affords the necessary protection to the patient. The cross connections between the time selector switch and the milliamperc selector switch which are shown are illustrative of what can be accomplished in this way and may be modified as desired. In practice both switches will generally have more contacts than are shown, giving a greater range of selection or selection by a greater number of steps and the cross connections will be arranged to provide the protection considered to be necessary in each case.

Attention is directed to the fact that the timer circuits are so designed that if any equipment item should become defective or fail to operate properly no exposure can be made and consequently there is no danger of an over exposure due to such defect or failure. That is, the timer circuit is so arranged that if it fails at all it fails safe. For example, if the tube 38 should become defective or if any relay should fail to operate no exposure can be made. A dirty contact at potentiometer 43 will open the cathode anode circuit so that no current can flow in this circuit and relay 40 cannot be energized. Still another example is the grid circuit of tube 38, which except for the connection through the contact arm 30 supplies a negative potential to the grid by way of resistors 31-35 and grid resistor 37. In case the contact arm 30 should fail to make a connection in some position due to a dirty contact or to maladjustment, the discharge circuit of the condenser 36 will be open but the circuit for placing a positive potential on the grid of the tube will also be open and the tube cannot pass current because of the negative potential on its grid.

My improved electronic timer is not limited to use for timing X-ray exposures but may be used in any situation where an accurate and economical timer is required for measuring short predetermined time intervals.

While certain specific values have been given herein, it will be understood that this has been done to facilitate the explanation and that other values may be used, when selected with the proper relation to each other. It will be understood also that other modifications may be made without departing from the principles of the invention and I do not therefore wish to be limited to the precise form of the invention as shown and described herein but desire to include and have protected by Letters Patent all forms and modifications of the invention that come within the scope of the appended claims.

60 I claim:

1. In an electronic timer, a condenser, a charging circuit for said condenser, a constantly closed discharge circuit for said condenser including a resistance, a timer switch for varying said resistance, means for opening said charging circuit to permit said condenser to discharge over said closed circuit, a space discharge device having a control grid, and a grid circuit connecting the positively charged terminal of said condenser to said grid and over which said condenser maintains a positive potential on said grid until it becomes discharged below a predetermined potential.

2. An electronic timer as claimed in claim 1, including means for maintaining a potential on

the cathode of said discharge device which is a sufficient number of volts positive to the potential on the negatively charged terminal of said condenser so that the discharge of said condenser to said predetermined potential is substantially linear.

3. An electronic timer as claimed in claim 2, including a common source of potential for charging the condenser and for the cathode of said discharge device, whereby an increase in the charging potential is compensated by an increase in the cathode potential.

4. In an electronic timer, a condenser, a charging circuit for said condenser, a discharge circuit for said condenser including a resistance, a timer switch for varying said resistance, a space discharge device having a control grid and a normally open anode circuit, means for impressing a potential on the cathode of said discharge device, a switching device which is positive with respect to the potential on the negatively charged terminal of said condenser for opening said charging circuit and closing said anode circuit while said discharge circuit is closed, and a grid circuit over which said condenser maintains a positive potential on said grid until it becomes discharged below the potential on said cathode.

5. A timer as claimed in claim 4, including a high resistance in the grid circuit to limit the grid current to a low value.

6. A timer as claimed in claim 4, wherein the switching device is self-restoring, and manually controlled means is provided for operating said switching device and maintaining it operated during the discharge of said condenser.

7. In an X-ray apparatus, a relay for controlling the duration of an exposure, a space discharge device having a control grid, an anode circuit for said device including said relay, a condenser, a charging circuit for said condenser, a discharge circuit for said condenser including a resistance, a timer switch for varying said resistance, a grid circuit over which the charged condenser impresses a positive potential on said grid, means for opening said charging circuit to permit said condenser to discharge, means for closing said anode circuit to energize said relay by current in said anode circuit, and means impressing a potential on the cathode of said device which is intermediate the potentials on the terminals of said condenser, whereby said relay is deenergized when the condenser becomes discharged sufficiently to reduce the grid potential below the cathode potential.

8. In an electronic timer, a space discharge device having a positively charged cathode, a condenser, a circuit for charging said condenser, a circuit including a resistance for discharging said condenser, a timer switch for varying the resistance of said discharge circuit, a circuit including said resistance for impressing on the grid a potential which is negative with respect to the cathode, and a circuit including said switch for causing said condenser to impress a positive potential on said grid while said condenser is charged above a predetermined potential.

9. In a timer, a relay to be energized for a desired time interval, a space discharge device having a cathode anode circuit including said relay, said circuit being normally open, a condenser, a charging circuit for said condenser, a time selector switch, a circuit including said switch connecting the positive terminal of said condenser with the grid of said space discharge device, means for opening said charging circuit and closing said

cathode anode circuit to energize said relay, and a discharging circuit for said condenser including a variable resistance the value of which is determined by the setting of said time selector switch, whereby said relay is deenergized after a desired time interval by the discharge of said condenser and the resulting change in the grid potential at said space discharge device.

10. In an electronic timer, a condenser, a circuit for charging said condenser, a circuit for discharging said condenser, a resistance and a time selector included in one of said circuits, said time selector being adjustable to regulate the effective value of said resistance, a space discharge device having a control grid, and a circuit including said time selector connecting one terminal of said condenser with said control grid and over which a charge in said condenser impresses a corresponding potential on said control grid.

11. In an electronic timer, a condenser, a circuit for charging said condenser, a discharge circuit for said condenser effective upon opening said charging circuit, a resistance, a time selector switch adjusted to include a varying amount of said resistance in said discharge circuit to regulate the discharge rate of said condenser, a space discharge device having a control grid, and a circuit including said time selector connecting one terminal of said condenser with said grid and over which said condenser maintains a positive potential on said grid until discharged below a predetermined potential.

12. In an electronic timer, a source of direct current, a condenser, a charging circuit connecting said condenser across said source, a time selection switch comprising a progressively movable contact arm and a plurality of fixed contacts operatively related thereto, a high resistance having a plurality of taps connected to said contacts, respectively, a space discharge device, a control circuit connecting the positively charged terminal of said condenser to the grid of said device, said control circuit including the contact arm of said switch, a fixed contact engaged thereby, and a portion of said resistance, and a discharge circuit for said condenser including said contact arm and contact and another portion of said resistance.

13. In an electronic timer, a source of direct current, a condenser, a charging circuit connecting said condenser across said source, a voltage divider bridged across said source, a space discharge device having its cathode connected to a point on said divider, a connection between the positive terminal of said condenser and the grid of said device, switching means for opening said charging circuit and connecting the anode of said device to the positive terminal of said source, thereby establishing current flow through said device, a relay energized by said current flow, and a circuit including a high resistance through which said condenser discharges to reduce the potential difference between the grid and cathode of said device, thereby reducing said current flow and deenergizing said relay.
